ATT'Y.

UNITED STATES PATENT OFFICE.

JOHAN M. ANDERSEN, OF BOSTON, MASSACHUSETTS, ASSIGNOR OF ONE-HALF TO ALBERT ANDERSON, OF SAME PLACE.

ELECTRIC SWITCH.

SPECIFICATION forming part of Letters Patent No. 598,553, dated February 8, 1898.

Application filed December 5, 1896. Serial No. 614,533. (No model.)

To all whom it may concern:

Be it known that I, JOHAN M. ANDERSEN, of Boston, in the county of Suffolk and State of Massachusetts, have invented an Improvement

5 in Electric Switches, of which the following description, in connection with the accompanying drawings, is a specification, like letters and figures on the drawings representing like parts.

10 This invention relates to electric switches, and is herein shown as embodied in a switch of that class known as "quick-acting;" and the said invention has for its object to provide a simple, efficient, and cheap switch in which the use of solder may be dispensed with.

15 Another feature of the invention consists in providing the members or parts of the switch with a cover, as will be described, whereby the uninsulated parts of the switch 20 are protected from dust, dirt, and accidental handling when the switch is in its operative or closed condition, and the said cover is provided with a movable portion attached to the movable member of the switch, so that the act 25 of uncovering the uninsulated parts of the switch opens the same.

In accordance with this invention the movable member or blade of the switch is composed of an inverted trough-shaped piece of 30 metal, comprising a back and two depending arms or sides, preferably of springy metal, such as copper, and the stationary or coöperating member is made of light shape, but preferably of composition metal, and comprising a back and two sides or arms, which 35 are integral with the said back, so that the use of solder and its attendant objections are avoided. The trough-shaped blade or movable member is preferably struck up with a 40 suitable die, and the stationary member is preferably machined or milled, and therefore these essential parts of the switch may be constructed with a minimum amount of labor and at a minimum cost.

45 These and other features of this invention will be pointed out in the claims at the end of this specification.

Figure 1 is a perspective view of one form of switch embodying this invention, the said 50 switch being open; and Fig. 2, a vertical section on the line 5 5, Fig. 1.

In the present instance I have chosen to illustrate my invention in a switch suitable for use in a three-wire system, but I do not desire to limit my invention to the particular 55 form shown.

Referring to the drawings, A represents a base, preferably of insulating material—such as slate, hard rubber, porcelain, &c.—upon which are suitably secured the stationary 60 members of the switch. In the present instance I have shown three sets of stationary members, and as they are of like construction I will specifically describe but one.

Referring to Fig. 1, a stationary member 65 comprises in the present instance two parts or pieces of metal *a a'*, each consisting of a back piece 2 and side arms 3 4, separated from each other. The back piece 2 of each part of the stationary member is preferably 70 made longer than the side pieces or arms 3 4 and is firmly secured to the insulated base A, as by countersunk screws. (Not herein shown.) The parts *a a'* of the stationary member may, and preferably will be, made of 75 a composition of metals and may be milled or otherwise machined from a solid piece or casting with a minimum amount of labor and at a minimum expense. The parts *a a'* of the stationary member have coöperating with 80 them a substantially trough-shaped movable member or blade, preferably of copper or like springy metal, and consisting of two side pieces or arms *b b'*, united or tied together by one or more back pieces *b²*, the said arms in the 85 present instance being integral with a single back piece *b²*, which may be secured, as by screws, to a cross-bar *b⁴*, preferably of insulating material. The substantially trough-shaped movable member of the switch may, 90 and preferably will be, made by striking up the same from a flat sheet or strip of metal, preferably copper, thereby enabling this part of the switch to be produced at a minimum cost with substantially little labor. The back 95 piece *b²* of the movable member is preferably made of sufficient width to enable the side arms *b b'* to embrace or make a sliding contact with the outside of the arms 3 4 of the parts *a a'* of the stationary member; but I 100 do not desire to limit my invention in this respect, as the arms *b b'* may make a sliding

contact with the inner sides of the arms 3 4. The movable member or blade of the switch is adapted to be engaged with and disengaged from the stationary member by means of an operating-lever *c*, preferably of the construction herein shown, the said lever being secured at its lower end (see Fig. 2) to the side arms 3 4 of the part *a'* of the stationary member by a pivot-pin *c'*, which is also extended 70 through the side arms *b b'* of the movable member or blade, and the said lever is provided near its pivot with a socket *c²*, extended from its rear side 6 toward its front side 7. (See Fig. 2.) The socket *c²* contains within 75 it a spring *c³*, which bears at one end against the back *b²* of the movable blade. The lever *c* is provided at its upper end with an arm *c⁴*, extended substantially at a right angle to the lever *c* and adapted to pass through the slot *c^x* in the back *b²* of the blade or movable member 80 and through a slot or opening *c⁵* in the movable portion *c¹⁰* of the cover, and the said arm has secured to it a handle *c⁶*, of insulating material. The arm *c⁴* is provided on its under side with a substantially central rib 20, (see Fig. 5,) which fits into the slot *c^x* in the back *b²* of the trough-shaped blade, and the said arm is also provided at its outer end with a depending flange 22, which overlaps the upper 85 end of the blade and constitutes a means for moving the blade or movable member from its open into its closed position. The arm *c⁴* of the lever *c* preferably has attached to it a guard *c⁷*, of insulating material, which is designed to cover the opening *c⁵* and prevent contact with the metal arm *c⁴* when the switch is in its closed position. The movable portion *c¹⁰* of the cover is fastened to the back *b²* of the movable contact member and has co- 90 operating with it a stationary portion *d*, removably secured, as by clips or hooks *d'* and screws *d²*, (see Fig. 1,) to the base A. The contact-piece *a'* of the stationary member has secured to it, as herein shown, a line-terminal 95 *d⁴*, which projects through a suitable slot or opening *d⁵* in the stationary portion *d* of the cover, and the movable portion *c¹⁰* of the cover is provided with a like slot or opening *d⁶*, which is adapted to fit over the other line-terminal *d⁷*, preferably secured, as by a countersunk screw *d⁸*, (see Fig. 2,) to a terminal plate *d⁹*, suitably secured to the base A, the said plate being designed in practice to be connected by a fusible wire or strip (not shown, but which may be of any suitable or usual construction) to the contact-piece *a* of the stationary member of the switch, the said fuse being adapted to be secured to the plate *d⁹* and contact-piece *a* by screws *d¹⁰ d¹²*. In 100 practice the terminals *d⁴ d⁷* are designed to be wound or covered with insulating-tape, so that when the switch is in its closed or operative position contact with the metal parts of the switch is prevented, thereby rendering this construction of switch especially desirable for use in dwelling-houses, shops, stores, and like places.

I prefer to use the cover, but the construction of the switch herein shown possesses advantages not dependent on the cover, and consequently the latter may be dispensed with, if desired. 70

In the present instance I have shown the movable member or blade of the center set of members and the lever *c* as pivoted to 75 the arms 3 4 of the contact-piece *a'* of the center set of stationary members, and the other movable members as connected to the center ones by the tie-bar *b⁴*.

When the switch is in its closed position 80 and if it is desired to open the same, the operator pulls upon the handle *c⁶*, which action moves the lever *c* toward the cover until the rear side 6 of the said lever engages the back *b²* of the movable member, which movement 85 of the said lever compresses the spring *c³*, and at or about the time the sides or arms *b b'* of the movable member or blade are disengaged from the arms 3 4 of the part *a* of the stationary member the spring *c³* acts and with 90 a quick motion throws the movable members or blades away from the arms 3 4 of the part *a* of the stationary member and opens the switch without danger of arcing. The switch may be closed by moving the handle *c⁶* in the 95 opposite direction, as above described.

By making the sides or arms 3 4 of the contact pieces or parts *a a'* of the stationary member in one piece with the back 2 the use of solder is avoided, which is desirable, for if 100 the arms should be soldered to the back 2 additional time and labor are required, and the solder is also liable to overheat and the arms become detached from the back if solder alone is depended upon to secure the said 105 arms to the back, and if the said arms are, in addition, pinned to the back additional labor and time are used in the manufacture of the switch.

I claim— 110

1. In an electric switch, the combination of the following instrumentalities, viz: a base, a stationary contact member secured thereto, a movable contact member co-operating with said stationary contact member, a cover of 115 insulating material comprising a stationary member attached to the base, and a movable member attached to said movable contact member to normally cover the said stationary contact member and to uncover the same when 120 the movable contact member is disengaged from the stationary contact member, substantially as described.

2. In an electric switch, the combination of the following instrumentalities, viz: a base, 125 a stationary contact member secured thereto, a movable contact member co-operating with said stationary contact member, an actuating-lever for said movable contact member, a spring interposed between said lever and 130 movable contact member, and a cover of insulating material attached to said movable member to move therewith to normally cover the stationary contact member and to uncover

said stationary contact member when the movable contact member is disengaged from the stationary contact member, and having a slot through which the actuating-lever extends, substantially as described.

3. In an electric switch, the combination of the following instrumentalities, viz: a stationary member composed of a back piece and side arms integral therewith and extended at an angle thereto, a movable member composed of a back piece and side arms integral therewith and extended at an angle thereto and adapted to make a sliding contact with the arms of the stationary member, an actuating-lever for said movable member provided with a socket, and a spring located in said socket and acting on said movable member, substantially as described.

4. In an electric switch, the combination of the following instrumentalities, viz: a stationary member comprising the parts *a a'*, each consisting of a back piece and side arms integral therewith and extended at an angle thereto, a movable member consisting of a back piece and sides or arms extended at an angle therefrom and adapted to engage the side arms of the parts *a a'* of the stationary member, a cover attached to said movable member and provided with an opening, an actuating-lever for the movable member provided with an arm extended through the opening in the cover, and with a socket, a spring in said socket acting on the movable member, a handle for the lever attached to the arm of the said lever, and a guard for the opening in the cover attached to the said lever, substantially as described.

5. In an electric switch, the combination of the following instrumentalities, viz: a sta-

tionary member comprising the parts *a a'*, each consisting of a back piece and side arms integral therewith and extended at an angle thereto, a movable member consisting of a back piece and sides or arms extended at an angle therefrom and adapted to engage the side arms of the parts *a a'* of the stationary member, a cover attached to said movable member and provided with an opening, an actuating-lever for the movable member provided with an arm extended through the opening in the cover, and with a socket, a spring in said socket acting on the movable member, a handle for the lever attached to the arm of the said lever, and a guard for the opening in the cover attached to the said lever, substantially as described.

6. In an electric switch, the combination of the following instrumentalities, viz: a stationary member composed of a back piece and side arms integral therewith and extended at an angle thereto, a movable member composed of a back piece and side arms integral therewith and extended at an angle thereto and adapted to make a sliding contact with the arms of the stationary member, an actuating-lever for said movable member, and a spring acted upon by said lever and acting upon the movable member, substantially as described.

In testimony whereof I have signed my name to this specification in the presence of two subscribing witnesses.
